UNITED STATES PATENT OFFICE.

JOHN ANDREW KNIGHT, OF MARLBORO, NEW HAMPSHIRE.

DESIGN FOR A BUCKET OR PAIL.

SPECIFICATION forming part of Design No. 34,207, dated March 12, 1901.

Application filed January 2, 1901. Serial No. 41,914. Term of patent 14 years.

To all whom it may concern:

Be it known that I, JOHN ANDREW KNIGHT, a citizen of the United States, and a resident of Marlboro, in the county of Cheshire and State of New Hampshire, have invented and produced a new, useful, and original Design for a Bucket or Pail, of which the following is a specification, reference being had to the accompanying drawing, the single figure of which is a perspective view of a bucket or pail the shape or configuration of which is in accordance with my invention.

As shown in the drawing, the distinctive or leading features of my invention are as follows: The bucket or pail comprises a plurality of side pieces or staves 1, having flat or plane surfaces, and the meeting edges 2 of which have interlocking projections, thus constituting a symmetrical body without hoops or bands. The meeting edges 2 of the plane sides converge toward each other

slightly from top to bottom, and their lower ends are fastened to an external polygonal bottom piece or plate 3.

It will be seen that the bucket or pail embodying my invention is unprovided with hoops or bands and that the form is useful as well as symmetrical in outline, and therefore pleasing in appearance.

Having described my invention, what I claim as new, useful, and original, and desire to secure by Letters Patent, is—

The design for a pail or bucket substantially as herein shown and described.

In testimony whereof I have hereunto subscribed my name this 24th day of December 1900.

JOHN ANDREW KNIGHT
